E. CROUSE.

GASOLENE DISPENSER.

APPLICATION FILED FEB. 12, 1921.

1,379,442.

Patented May 24, 1921.

By *A. J. Crouse*
Attorney

UNITED STATES PATENT OFFICE.

EMORY CROUSE, OF WICHITA, KANSAS.

GASOLENE-DISPENSER.

1,379,442.

Specification of Letters Patent. Patented May 24, 1921.

Application filed February 12, 1921. Serial No. 444,387.

To all whom it may concern:

Be it known that I, EMORY CROUSE, a citizen of the United States, residing at the city of Wichita, county of Sedgwick, and State of Kansas, have invented certain new and useful Improvements in Gasolene-Dispensers; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 The object of this invention is to provide a dispensing device for gasolene to be used at filling stations, wherein means is provided at the outer end of a flexible dispensing hose for the control of a motor or other means 20 which is employed for refilling the container at the top of the dispensing device from which the gasolene is directly dispensed.

In this form of construction, the dispensing hose is provided on its outer end with a discharge nozzle having a control valve so that the dispensing operation is controlled at the discharge end of said hose. The present invention resides in providing means on said hose adjacent said nozzle for controlling the operation of a pump or the like to refill the dispensing container at the top of the apparatus without making it necessary for the operator to leave his position at the gasolene tank of an automobile. As is frequently the case, such a gasolene tank has a capacity greater than the capacity of the dispensing container above mentioned, and heretofore it has been necessary for the operator to return to the device in order to refill the container. With the present means, necessity for this is eliminated.

In the accompanying drawings, in which certain embodiments of this invention are disclosed,

Figure 1 is an elevation of a complete dispensing device equipped with the present invention;

Fig. 2 is a detail of the switch-operating means;

Fig. 3 is a detail of the modification;

Fig. 4 is a detail of a further modification; and

Fig. 5 is a detail partially in section of the operating means on the outer end of the dispensing hose.

In Fig. 1 a framework 10 is shown mounted upon a base 12 for supporting the structure, the upper end of this framework being connected to a head 14 having an integral bowl 15, a partitioning bottom 16 being provided approximately midway of the head and bowl. In practice the parts within the framework 10 are inclosed in a metallic housing, which has been omitted from the drawings for sake of clearness. A cylindrical glass container 18 is sealed upon the top of the bowl 15 and is provided with a cover 19, the parts being securely retained in operative relation by means of a tie-rod or draw-rod 20 whose lower end is fixed in the partitioning bottom 16 and whose upper end is fixed to said cover 19. An air valve 21 is conveniently provided in said cover 19. A crown 22 is provided at the top of the transparent container 18 and carries there above a large globe 23 which receives a crown light 24, and in practice may carry advertising display. For purposes of illumination, a series of small lights 25 are provided on the under side of the crown 22, all of these lights being supplied through wires contained in conduits 26 connected with a main system of conduits 27. The upper branch of the conduit system 27 is provided with a switch 28 to control the lights 24 and 25.

A filling pipe line 30 is provided, its upper end passing through the bottom 16 and its lower end leading to a pump 31 driven by an electric motor 32 receiving the supply of gasolene through a pipe 33 connected with a supply or storage tank, not shown. An overflow pipe 34 also extends through said bottom 16 to a point adjacent the top of the transparent container 18, the top of this pipe determining the height of the gasolene within said container. A drain line 35 has its upper end also connected with said bottom 16 and its lower end connected with the overflow pipe 34 by means of a T 36, a valve 38 being provided in said drain line 35 to close the same normally. The overflow pipe 34 is connected with the storage tank, not shown, to return gasolene thereto. A connection 40 is also let into said bottom 16 and leads to a special meter 41 whose lower end communicates with a return bend 42 having at its outer end a valve 43 opposite the meter 41. From the lower side of this valve 43, the flexible dispensing hose 44 leads and is equipped at its free end with a valve-controlled nozzle 45 oper-

able by a handle 46 in well-known fashion. Adjacent said valve-controlled nozzle 45 the hose 44 is provided with a protecting sleeve or shield 48 upon which there is slidably 5 mounted a hand-grip 49 connected with an operating cable 50 slidable in a guide tube 51 secured to the hose 44 and extending the length thereof. At the upper end of the hose a small pulley 52 is provided over 10 which the cable 50 passes to the free end of a lever 53, which is fulcrumed at 54 on an arm 55 secured to the conduit 27, which receives the wires W for supplying electric current. The lever 53 is provided with 15 an operating spindle 56 which extends into a switch S on the conduit 27 for the purpose of controlling the flow of current. A spring 57 is disposed between the switch S and the lever 53 for the purpose of opening 20 the switch when it is not positively operated by draft upon the cable 50 from the hand-grip 49. To insure opening of said switch, a second spring 58 may conveniently be provided, one end of which bears against 25 the lever 53, said spring being mounted upon a pin 59 secured at 60 to the conduit 27. This switch S controls the flow of current 30 through a system of wiring within the conduit 27 and in a branch conduit 127 which leads directly to the electric motor 32.

In operation of the device, the transparent container 18 is filled through pipe 30 by operation of the motor 32, the level within the container being determined by the over-flow pipe 34. The container is also adapted to be drained through the line 35 and valve 38. These features in general are disclosed in my former Patent No. 1,304,028 of May 20, 1919. The gasoline in the container 18 35 is then discharged through the nozzle 45 into the automobile gasoline tank, graduations being provided on said container 18 to indicate the amount so dispensed. The container 18 may then be refilled without the 40 operator's leaving his station at said automobile gasoline tank, by grasping the hand-grip 49 and sliding it outward on said hose 44, so as to cause the cable 50 to move the lever 53 inward to close the switch S. This 45 position is maintained until the pump 32 has refilled the container 18 when said grip 49 is released.

In addition to the preferred form above described, an electric switch 65 may be provided adjacent said nozzle 45, as shown in Fig. 4, the electric wires W being housed in a flexible conduit 66 on the hose 44. With this construction, the wires W will lead directly through the conduit 27 to the 50 motor 32.

In Fig. 3 a further modification is disclosed, wherein the cable 50 which is operated by the hand-grip 49 as in Figs. 1 and 5, has its upper end provided with a clip 70 65 engaging with the outer end of a short arm

72 secured upon a rotary rod 74 controlled by a coiled spring 75, the upper end of which is fixed to a boss 76 projecting from the casing of an air valve 78. The rod 74 may be rotated by draft upon the cable 50 70 against the tension of spring 75, and when released will be returned by said spring 75. Any design of air valve 78 may be used which will upon rotation of the rod 74 permit the passage of air through a compressed 75 air line 80 past said valve and thence through a line 82 into the storage tank, not shown as above indicated, whereby gasoline will be forced up through a filling pipe line corresponding to conduit 33 and line 30 80 into the container 18. When the valve is released and returned by spring 74 to its normal position, it will relieve the pressure in the storage tank back through the line 82 and to exhaust by way of an air exhaust 85 line 84.

From the foregoing it will be seen that I have provided means, capable of several embodiments, for directly controlling the filling of a dispensing container from the 90 outer or free end of a flexible dispensing hose.

I claim:

1. A liquid dispensing apparatus comprising a container, a liquid supply from 95 which to fill said container, means operable to cause liquid to be moved from said supply to the container, a flexible conduit for discharge of liquid from said container, a valve on the outer end of said conduit to 100 control said discharge, and means adjacent said valve to control said operable means, whereby filling of said container may be controlled from said outer end of said flexible conduit.

2. A liquid dispensing apparatus comprising a container, a liquid supply from 105 which to fill said container, means operable to cause liquid to be moved from said supply to the container, a flexible conduit for discharge of liquid from said container and means mounted on said conduit to control 110 said operable means, whereby filling of said container may be controlled from the outer end of said conduit.

3. A liquid dispensing apparatus comprising a liquid container, a liquid supply connected with said container, means to move liquid from said supply to said container to fill the latter, a flexible conduit 120 connected with said container, a valve on the free end of said conduit to control discharge of liquid from the container through the conduit, and means mounted on said conduit adjacent said valve for controlling 125 said liquid moving means whereby filling of said container is controllable from said free end of said conduit.

In testimony whereof I affix my signature.
EMORY CROUSE.
